HEDDLE BAR SUPPORT

Frederick M. Suchke, Atlanta, Ga., assignor to
Pioneer Heddle & Reed Co., Inc., Atlanta, Ga.

Application May 5, 1949, Serial No. 91,549

2 Claims. (Cl. 139—92)

1

This invention relates to heddle bar supports. In heddle frames for loom harness, the heddles are mounted on a pair of parallel bars supported between the sides of the frame, and certain of the heddles now in use have substantially C-shaped ends which engage over the heddle bars. The heddle bars are secured to supporting members by screws which are in line with the openings in the heddle ends, but under vibration these screws frequently become loose and cause damage to the fabric. It is, therefore, an object of this invention to provide a support for a heddle bar which can be adjusted at any point along the frame and embodies a latched hook formed of thin metal so that the adjacent heddles will not be bunched or dislocated, and if desired several of the supports may be used along the length of the bar.

Another object of this invention is to provide a heddle bar or rod support which can be used on either metal or wooden frames of the type at present in use.

With the above and other objects in view, my invention consists in the arrangement, combination and details of construction disclosed in the drawings and specification, and then more particularly pointed out in the appended claims.

In the drawing,

Figure 1 is a fragmentary detail front elevation of a heddle frame having a heddle bar supporting means constructed according to an embodiment of this invention mounted thereon,

Figure 2 is a fragmentary sectional view taken on the line 2—2 of Figure 1,

Figure 3 is a fragmentary end elevation of the supporting means,

Figure 4 is a fragmentary sectional view taken on the line 4—4 of Figure 3,

Figure 5 is a sectional view showing a modified form of heddle bar support.

Referring to the drawing, the numeral 10 designates generally a heddle frame which has extending thereacross a pair of heddle supporting bars 11, one of such bars being here shown. It will be understood that the heddle frame 10 is of rectangular configuration and includes upper and lower frame bars 12 and upper and lower supporting bars 11.

A plurality of heddles 13 are adapted to be disposed between the heddle supporting bars 11 and each heddle is formed with a substantially C-shaped head 14 at each end thereof through which the supporting bar 11 is adapted to loosely engage.

In order to provide a means whereby the sup-

2

porting bar 11 will be held against longitudinal bending I have provided a bar supporting means generally designated as 15. The bar supporting means 15 includes a strap or bar 16 formed with a C-shaped opening 17 having a lower bill 18 formed integral therewith. The bar or strip 16 at its outer end is formed with a right angular extension 19 which is adapted to be fixed to the bight 20 of a U-shaped slide 21 by fastening means 22.

The slide 21, as shown in Figure 3, is formed with substantially T-shaped slots 23 in the parallel legs 24 thereof, and a T-shaped guide bar 25 is secured in any suitable manner to the heddle frame member 12, with the flanged head thereof innermost and the legs 24 of the slide 21 loosely engaging the flanges 26 of the T-bar 25.

The supporting member 16 also includes a spring-pressed pivoted outer bill 27 which is carried by a U-shaped member 28 pivoted on pivot members 29 carried by the outer portion of the bar or strap 16. The pivoted bill 27 is constantly urged to latching or operative position by means of a flat bowed spring 30 which engages within the U-shaped member 28 and is secured by fastening means 31 to the bight 20 of the slide 21. By providing the latching bill 27 the heddle bar 11 can be readily disengaged, from the support 15 without pulling the bar endwise completely through the heddle frame.

Referring now to Figure 5, there is disclosed a modified form of this invention wherein the heddle bar is supported from a supporting means adapted to be screwed into the frame bar 12. In the present instance the C-shaped support bar or strap 16a is constructed similar to the strap 16 and is provided with a spring-pressed latching bill 27a. The shank 32 of the bar or strap 16a is formed at the upper end thereof with a screw shank 33 which is adapted to be screwed into an adjacent heddle frame member 12a. The latching bill 27a is constantly urged to latching position by means of a bowed spring 30a which in the present instance has the outer end thereof secured by means of a screw or other fastening means 34 to the inner edge of the frame member 12a.

With a heddle bar supporting means as shown in Figures 1 to 4 inclusive, the supporting means may be adjusted to any point along the length of the heddle bar 11, and inasmuch as the bar supporting strap or member 16 is formed of relatively thin metal, the supporting member when 55 in applied position will not space the adjacent

heddles 13 an undue distance apart so as to thereby affect the character of the fabric which is being woven. It will be understood that the supporting hook or strap 16 may be formed of tempered metal so that it can be made of sufficient thin material to eliminate undue spacing of the heddles. When it is desired to remove the heddles from the heddle bar or to adjust the spacing thereof, the heddle bar 11 may be rocked forwardly as viewed in Figure 1, with the latching bill 27 swung upwardly to released position. The structure shown in Figures 1 to 4 inclusive may be used with either metal heddle frames or combined wood and metal frames, whereas the structure shown in Figure 5 is designed for use with wooden heddle frames. The structure shown in Figure 5 can be easily and quickly mounted on the present structure of wooden heddle frames for firmly supporting the heddle bar, and it will be understood that one or more of these supporting members may be mounted in the heddle frame so as to support the heddle bar in proper position within the heddle frame.

I do not mean to confine myself to the exact details of construction herein disclosed, but claim all variations falling within the purview of the appended claims.

What I claim is—

1. In a heddle frame structure having a frame member, a pair of heddle bars and heddles disposed between and engaging the bars; a supporting means for the heddle bars, said supporting means comprising a strap formed with a C-shaped opening in which the heddle bar is adapted to engage, a U-shaped slide member fixed at the bight thereof to said strap, the legs of said

slide member being formed with T-shaped slots, and a T-shaped bar fixed to said frame and engageable with said slide member.

2. In a heddle frame structure having a frame member, a pair of heddle bars and heddles disposed between and engaging the bars; a supporting means for the heddle bars, said supporting means comprising a strap formed with a C-shaped opening in which the heddle bar is adapted to engage, said strap including a spring-pressed latching bill, a right angular extension carried by said strap, a U-shaped slide fixed at the bight thereof to said extension and having T-shaped slots in the ends of the legs thereof, and a T-shaped guide fixed to said frame with which said slide is adapted to engage.

FREDERICK M. SUCHKE.
